UNITED STATES PATENT OFFICE.

RICHARD PINKNEY JONES, OF WASHINGTON, DISTRICT OF COLUMBIA.

FLUSHING APPARATUS.

SPECIFICATION forming part of Letters Patent No. 732,416, dated June 30, 1903.

Application filed August 8, 1902. Serial No. 118,890. (No model.)

To all whom it may concern:

Be it known that I, RICHARD PINKNEY JONES, a citizen of the United States, residing at Washington, in the District of Columbia, 5 have invented certain new and useful Improvements in Flushing Apparatus, of which the following is a specification.

My invention relates to flushing apparatus for cleaning the floors of rooms in residences 10 or other buildings, and its object is to provide simple but effective means for thoroughly cleansing floors.

The invention comprises gutters or water-passages extending along the sides of a room 15 adjacent to the base-board thereof and having water-discharge openings.

The invention also consists of certain details and features of construction which will be fully described hereinafter and defined in 20 the appended claims in connection with the accompanying drawings, which form part of this specification, and in which—

Figure 1 is a plan view of a floor provided with my improvements. Fig. 2 is a section 25 on the line 2 2 of Fig. 1, and Fig. 3 is a section on the line 3 3 of Fig. 1.

Corresponding parts in all the figures are denoted by the same reference characters.

The reference-numeral 1 designates the 30 floor of a room formed at each of its four sides adjacent to the base-board with a groove 2 to receive a gutter or water-conduit 3, which is of concavo-convex form in cross-section to fit the groove and has its edges approximately 35 flush with the surface of the floor. The meeting ends of the gutter-sections are mitered, as shown, to insure a close joint. After the gutter-sections are placed in position their abutting ends are secured together in a water-tight manner by cement or other suitable 40 sealing material. Each of the gutter-sections is preferably formed with a deflector-rib 4, projecting upward from the gutter and inclining downward from opposite sides of the center to the ends of the section and gradually 45 increasing in width from the center to the ends of the section. These deflector-ribs being narrow or pointed at the center and sloping down to almost no height where they meet 50 the openings serve to effectually accelerate the flow of water toward the outlets.

The numeral 5 designates water-discharge openings formed one at each corner of the room through the floor and the ends of the gutter-sections are recessed to form openings 55 registering with the floor-openings. The outlets 5 are each provided with a hinged cover 6, which may be readily opened or closed.

Each of the gutter-sections is provided with a cover comprising a strip or plate of metal 60 8, formed with perforations for the passage of water, said strips being of such length as to fit snugly together at their meeting ends and of sufficient width to cover the gutter-sections. 65

The utility of the invention will be readily understood and appreciated. It permits a floor to be flushed with water and thoroughly cleansed, the waste water passing off freely.

While the improvement is designed for use 70 in residences and buildings generally, it is especially well adapted for stores, saloons, and like public rooms where frequent cleaning is necessary.

I would have it understood that the invention is not restricted to the exact construction 75 illustrated in the drawings, but that it includes all such minor changes and modifications as may fall within the scope of the following claim. 80

Having thus described my invention, I claim and desire to secure by Letters Patent—

The combination with a floor formed along 85 its sides with grooves or depressions, of gutter-sections supported within said grooves and provided with outlet-openings, deflecting-ribs narrow or pointed at the center and sloping downward toward said outlet-openings, covers for said openings, and removable perforated covers for the gutter-sections. 90

In testimony whereof I have signed my name in the presence of the subscribing witnesses.

RICHARD PINKNEY JONES.
